CLAIM

The ornamental design for a wireless sensor, as shown and described.

DESCRIPTION

FIG. 1 is a top perspective view of a first embodiment of the wireless sensor showing a new design;
FIG. 2 is a bottom perspective view of the first embodiment;
FIG. 3 is a top view of the first embodiment;
FIG. 4 is a bottom view of the first embodiment;
FIG. 5 is a front view of the first embodiment;
FIG. 6 is a rear view of the first embodiment;
FIG. 7 is a left view of the first embodiment;
FIG. 8 is a right view of the first embodiment;
FIG. 9 is a top perspective view of a second embodiment of the wireless sensor showing another new design;
FIG. 10 is a bottom perspective view of the second embodiment;
FIG. 11 is a top view of the second embodiment;
FIG. 12 is a bottom view of the second embodiment;
FIG. 13 is a front view of the second embodiment;
FIG. 14 is a rear view of the second embodiment;
FIG. 15 is a left view of the second embodiment; and,
FIG. 16 is a right view of the second embodiment.
The broken lines depict unclaimed environmental subject matter.
